UNITED STATES PATENT OFFICE.

ROBERT N. THOMAS, OF SHENANDOAH, IOWA.

CORN-HUSKER.

SPECIFICATION forming part of Letters Patent No. 758,196, dated April 26, 1904.

Application filed June 2, 1903. Serial No. 159,770. (No model.)

To all whom it may concern:

Be it known that I, ROBERT N. THOMAS, a citizen of the United States, residing at Shenandoah, in the county of Page and State 5 of Iowa, have invented a new and useful Improvement in Corn-Huskers, of which the following is a specification.

My invention relates to corn-huskers, and especially to that type of huskers which are 10 employed in husking by hand, and has for its objects to produce a device of this character which will be simple in construction, efficient in operation, one in which the husking-plate will conform to and fit snugly the palm of the 15 hand, and one in which the said plate is provided with a plurality of husk-engaging spurs or fingers which in practice will be firm and rigid, thus acting more effectively upon the husks for removing the same.

20 To these ends the invention comprises the novel details of construction and combination of parts more fully hereinafter described.

In the accompanying drawings, Figure 1 is 25 a perspective view illustrating my improved device as applied to the hand. Fig. 2 is a top plan view of the device removed. Fig. 3 is a detail sectional elevation longitudinally through the plate.

30 Referring to the drawings, 1 indicates a flexible member, composed of leather or other suitable material, comprising a wristband 2 and an integral flap 3, which in practice overlies the palm of the hand. To one end of the wristband 2 I secure by rivets, eyelets, or the 35 like a pair of straps 4, which adjustably engage oppositely-disposed buckles 5, associated in any suitable manner with the other end of the wristband for securing the latter around the wrist of the operator when the de- 40 vice is in use.

45 6 indicates a plate of any suitable metal which is secured by rivets or otherwise to the flap 3 and from which is struck up a pair of husk-engaging spurs or fingers 7, which curve upward and backward from the plate 6 and have their rear husk-engaging ends pointed or sharpened, as at 8, to permit them to readily enter and rend the husks. In this connection attention is directed to the fact that 50 the spurs, being formed integral with the

plate, will in practice be extremely firm and rigid, thus obviating liability of them yielding or breaking under the strain due to tearing of the husk away from the ear. It is further to be noted that owing to providing 55 the plate with a pair of the spurs a more secure hold upon the husk is obtained, with a consequent increase in speed during the husking operation and a more thorough and positive removal of the husks. 60

9 is a strap secured to the outer end of the flap 3 between the same and the plate 6, said strap being attached to said parts by means of a pair of the rivets, which serve to secure the plate to the flap. This strap in practice 65 is secured around the hand for attaching the husker thereto.

The inner end of the plate 6, which normally overlies the palm of the hand at the base of the thumb, is of concavo-convex form, as 70 shown more clearly in Fig. 3, and is in practice disposed with its concaved side adjacent to and fitting snugly upon the curved surface of the palm at the base of the thumb. This curving of the plate to fit the palm not only 75 renders the device more comfortable to the operator, but also to a material extent obviates slipping of the device relative to the hand while acting upon the husks, thus assisting the removal of the latter and preventing chaf- 80 ing of the hand of the user.

In practice the corn to be husked is grasped by the left hand, and the right hand, having my attachment applied thereto, is drawn downward longitudinally of the ear, which action 85 causes the spurs 7 to engage and slit the husk and remove the same from and expose the ear, which latter is then grasped by the right hand and broken off from the husk as usual. In this connection attention is directed to the 90 fact that when my device is applied to the hand of the operator the spurs 7 will occupy a position to permit free closing of the hand without the fingers coming in contact with the spurs, thus permitting ready grasping of 95 the ear to remove the same from the husk, as above described.

From the foregoing it will be seen that I produce a device which is simple of construction and one which will in practice efficiently 100

perform its functions, and it is to be understood that I do not limit myself to the precise details herein shown, inasmuch as changes in the form, proportion, and manner of assemblage of the parts may be resorted to without departing from the spirit of my invention.

Having thus described my invention, what I claim is—

A device of the class described comprising a flexible member consisting of a wristband and an approximately centrally disposed integral flap projecting substantially at right angles therefrom to overlie the palm, a plate attached to the flap and having an integral 15 husk-engaging spur struck up therefrom, said plate being of concavo - convex form and

arranged with its concaved face inward to conform to the curvature of the palm at the base of the thumb, oppositely-disposed coöperating straps and buckles associated with the 20 opposite ends of the wristband, and a strap secured between its ends to the outer end of the flap between the same and the overlying plate.

In testimony that I claim the foregoing as 25 my own I have hereto affixed my signature in the presence of two witnesses.

ROBERT N. THOMAS.
